UNITED STATES PATENT OFFICE.

JAMES WILLIAM HARRISON, OF ATLANTA, GEORGIA, ASSIGNOR OF ONE-HALF TO A. DAWSON, OF ATLANTA, GEORGIA.

CINDER-GUARD FOR CARS.

SPECIFICATION forming part of Letters Patent No. 764,462, dated July 5, 1904.

Application filed April 18, 1903. Serial No. 153,254. (No model.)

To all whom it may concern:

Be it known that I, JAMES WILLIAM HARRISON, of 13 Middle street, Atlanta, in the county of Fulton, State of Georgia, have invented certain new and useful Improvements in Cinder-Guards for Cars, of which the following is a complete specification, reference being had to the accompanying drawings.

My invention relates to improvements in cinder-guards for cars, particularly postal cars, and has for its object the production of a combination guard and mask, the guard being provided with a glass wall which the mask upon the guard is designed to protect.

15 A device of the same general class to which my invention belongs is shown in United States Letters Patent No. 541,144, issued June 18, 1895.

20 In the accompanying drawings, Figure I is a sectional view of my device complete, taken upon the line I I of Fig. II and illustrated as attached to a door-jamb. Fig. II is a front elevation of my device complete, but detached. Fig. III is an end view illustrating the co-operation of the mask-spring with the door-jamb.

25 Referring to the numerals on the drawings, 1 indicates a door-jamb (see Figs. I and II) to which a metallic guard 2 of any suitable or preferred conformation is secured, as by 30 means of the well-known attaching devices 3. The attaching devices are such as permit of the ready installation or removal of the guard as required, it being necessary in practice to transfer the guard from one door-jamb to another whenever the direction of movement of the car is reversed.

35 5 indicates the front wall, usually made of glass, which, mounted in the guard 2, constitutes the transparent protective member behind which a person may take observations from a moving car.

40 One feature of my invention consists in the provision made for mounting the glass 5 in the guard 2. The same consists of a circum-45 ambient flange 6 upon the guard 2, with which co-operates a similar flange 7 to hold the glass in place. The flange 7 is mounted upon a plate 8, which may be provided with a stiffen-

ing-flange 9. The plate 8 need not extend entirely around the inner wall of the guard 2, but need only be coextensive with the outer wall thereof. The plate 8 not only constitutes a convenient means for securing the glass 5 in place, but it affords a reinforcement for the guard 2, so that it may present the requisite firmness and rigidity at points where such qualities are demanded, and that without material increase in the weight of the entire guard, which, as has been already specified, should be readily portable.

45 It is necessary to protect the observer behind the guard from serious injury which might ensue in consequence of the accidental breaking in service of the glass 5. For that reason I provide as a glass-protector a mask 10, which is preferably made of heavy wire suitably braced and reinforced and of any preferred conformation and configuration. A particular description of the mask 10 is unnecessary, because it is well known in the art. Suffice it to say that the mask is preferably provided with a back rod 12, consisting of a straight section of wire and a curved base-piece 15, united to the rod 12, as by terminal bends or eyelets 16, formed near the opposite ends of said rod.

50 Heretofore, as above suggested, masks have been employed to protect the glass plate of cinder-guards; but they have been made separate from the guard, thereby necessitating individual attention and manipulation whenever shifting of position of the guard becomes necessary. In consequence the masks are frequently lost, and by such loss in transit the plate 5 is often left unprotected, resulting not infrequently in serious injury to the observer behind the guard.

55 By my invention the mask and the guard are combined. I prefer to combine them by the employment of properly-disposed lugs 17 of suitable length, pivoted, respectively, in coaxial alinement to the opposite ends of the guard 2. For this reason each lug is preferably provided with a terminal eyelet 18, through which one of the bolts 19, which serve to secure the plate 8 to the guard 2, is passed.

Each of the bolts 19 is provided with means for securing it in place, preferably a nut 20 on its inner end. The special function of the plate 8 in lending the required firmness and rigidity to the guard 2 is made apparent when it is considered that it affords a supporting-base for the mask 10.

The mask is pivotally united to the guard 2 in order to provide for the swinging back 10 of the mask from in front of the plate 5 in order to permit the cleaning of the face of said plate, which in practice frequently becomes necessary. The mask is for like reasons preferably held yieldingly in front of the plate 5, 15 as by a spring-clip 21, secured to the mask in such a manner as to resiliently engage a member relatively fixed with respect to the guard—for example, the face of the jamb 1, which is obviously fixed with respect to the guard when

the guard is in service and the clip is required 20 to perform its function.

The operation of my device being apparent from the foregoing specification, further detailed description thereof is deemed unnecessary.

25

What I claim is—

The combination with a guard, transparent front wall and reinforcing-plate secured to the guard, of a mask and means for pivotally uniting the mask to the reinforcing portion of 30 the guard.

In testimony of all which I have hereunto subscribed my name.

JAMES WILLIAM HARRISON.
